CLAIM

The ornamental design for a rotation knob for a clip applier, as shown and described.

DESCRIPTION

FIG. 1 is a perspective view of a rotation knob for a clip applier;

FIG. 2 is a back view of the rotation knob for the clip applier of FIG. 1;

FIG. 3 is a front view of the rotation knob for the clip applier of FIG. 1;

FIG. 4 is a right side view of the rotation knob for the clip applier of FIG. 1;

FIG. 5 is a left side view of the rotation knob for the clip applier of FIG. 1;

FIG. 6 is a top view of the rotation knob for the clip applier of FIG. 1; and,

FIG. 7 is a bottom view of the rotation knob for the clip applier of FIG. 1.

The broken lines in the drawings form no part of the claimed design.
